UNITED STATES PATENT OFFICE

166,925

FLOWER POT OR SIMILAR ARTICLE

Nathan W. Roop, Columbus, Ohio, assignor to Columbus Plastic Products, Inc., Columbus,
Ohio, a corporation of Ohio

Application August 23, 1950, Serial No. 11,883

Term of patent 14 years

(Cl. D35—3)

To all whom it may concern:

Be it known that I, Nathan W. Roop, a citizen of the United States, residing at Columbus, in the county of Franklin and State of Ohio, have invented a new, original, and ornamental Design for a Flower Pot or Similar Article, of which the following is a specification, reference being had to the accompanying drawing, forming a part thereof.

Fig. 1 is a perspective view of a flower pot, showing my design;

Fig. 2 is a side elevational view;

Fig. 3 is a top plan view;

Fig. 4 is a bottom plan view.

I claim:

The ornamental design for a flower pot or similar article, substantially as shown.

NATHAN W. ROOP.
